MOTION CONVERTING MECHANISM

Jens A. Paasche, Chicago, Ill., assignor to Cline Electric Manufacturing Company, Chicago, Ill., a corporation of Illinois

Application June 17, 1952, Serial No. 294,039

14 Claims. (Cl. 74—99)

This invention relates to oscillatory coating apparatus and more particularly to a cam and cam follower mechanism for use in controlling the operation of spray guns in oscillatory coating apparatus.

In certain types of continuous coating processes oscillating devices are used in combination with endless work conveyors. The spray guns of the coating apparatus and the article are moved relative to each other, the spray guns being swept from one side of the article to be coated to the other. In order to save paint or other material being sprayed, it is desirable to interrupt the operation of the spray guns when they approach the edge of the article being coated. Inertia of the parts and the time required for the material being sprayed to move from the exit orifices of the spray guns to the article to be coated necessitate interruption of the flow of coating material before the guns are positioned over the edge of the article. After turning off the flow of coating material the spray guns are carried past the edge of the article. Movement of the guns is then reversed and the guns are moved toward the article and then across the article. It is necessary to initiate flow of coating material at such a time that the material strikes the edge and fully coats the edge of the article. It has been found that the point of interruption of the flow of coating material and the point at which flow of material must be initiated do not coincide.

Accordingly it is an object of the present invention to provide a control mechanism for spray guns of the type set forth that will effect an economy of material being sprayed.

Another object of the invention is to provide control mechanism for spray guns which can selectively turn off and turn on the flow of coating material so that the stream of coating material hitting the article to be coated is interrupted and again initiated at the precise desired point.

Yet another object of the invention is to provide in a control apparatus of the type set forth cam and cam followers which are individually and universally adjustable whereby to obtain the necessary degree of control.

A further object of the invention is to provide an improved double acting cam and cam follower arrangement which will achieve the objects set forth above.

Although the control mechanism of the present invention has general application, its advantages are most fully realized when the control mechanism is used in conjunction with a spray coating apparatus. Accordingly, the mechanism is hereinafter described in conjunction with such a spray coating apparatus.

A still further object of the invention is to provide an improved carriage for use in spraying apparatus of the type set forth.

The above and other objects of the invention will be more fully understood from the following description when taken in conjunction with the accompanying drawings. In the drawings wherein like reference numerals have been used to indicate like parts throughout:

Fig. 1 is an elevational view partly in cross section illus-

2

trating a spraying apparatus incorporating therein the control mechanism of the present invention, the spraying apparatus being shown in operative position over a conveyor carrying articles to be sprayed;

5 Fig. 2 is a view in vertical section substantially as seen in the direction of the arrows along the lines 2—2 of Fig. 1;

10 Fig. 3 is a diagrammatic view on an enlarged scale of the cam and cam follower mechanism of the present invention, the various parts being shown in the different operating positions that are assumed by these parts during a control cycle;

15 Fig. 4 is an enlarged view partly in section of the cam meter utilized in this invention;

20 Fig. 5 is a view in vertical section substantially as seen in the direction of the arrows along the line 5—5 of Fig. 4;

25 Fig. 6 is a fragmentary view showing the manner in which the cam follower actuates the control valve of the present invention, the control valve being shown in cross section; and

30 Fig. 7 is an enlarged view in vertical section of the cam follower of the present invention substantially as seen in the direction of the arrows along the line 7—7 of Fig. 3.

35 Referring now to the drawings and more particularly to Fig. 1, there is shown an oscillatory spraying apparatus including as a part thereof a control mechanism made in accordance with and embodying the principles of the present invention. The spraying apparatus includes generally a conveyor 10, an oscillatory spraying unit 12, a frame 14 for supporting spraying unit 12, and a pair of control cam units 16 and 18. Conveyor 10 includes a pair of legs 20 on which are mounted a pair of spaced apart flanges 22 and 24. Mounted between the flanges 22 and 24 are chains 26 and 28, one of the chains being positioned along either side of and supporting a work support member 30. Mechanism (not shown) is provided to drive the chains 26 and 28 whereby to move them 40 within the support flanges 22—24. The support member 30 is adapted to receive and carry a work piece 32. As viewed in Fig. 1, the support member 30 and associated parts are moved in a direction perpendicular to the sheet and out of the sheet whereby to carry the work piece 32 in a uniform manner beneath the oscillatory spray unit 12.

45 The oscillatory unit 12 is mounted upon the frame 14. Frame 14 includes a pair of base members 34 and 36 which are positioned on opposite sides of the conveyor 10 but positioned adjacent thereto. The upper ends of base members 34 and 36 are hollow whereby to receive a pair of upstanding end members 38 and 40. The end members 38 and 40 are telescopically received in and adjustable in the upper ends of the bases 34 and 36. Clamp members 42 and 44 are provided 50 to lock the end members 38 and 40 in any desired position within the base members 34 and 36 respectively. The upper ends of end members 38 and 40 are provided with hemispherical caps 46 and 48 which close the ends of these members. Each of the end members is 55 provided with a pair of bosses, these bosses being hollow and having an axis extending substantially perpendicular to the longitudinal axis of the associated end member. End member 38 is provided with bosses 50 and 52 and end member 40 is provided with bosses 54 and 56. The bosses 50 and 54 which are positioned adjacent the upper ends of the end members 38 and 40 support an upper support member or track 58. The ends of tracks 58 are threaded received by the bosses 50 and 54 and are held in firm relationship thereto by 60 means of hexagonal nuts 60 and 62. The lower bosses 52 and 56 similarly support a lower track 64 whose ends are threaded received by the bosses and held in

position by hexagonal nuts 66 and 68. The tracks 58 and 64 are spaced apart a fixed distance at each end and extend parallel to each other throughout their entire length. Each of these tracks is preferably formed as a hollow tube or pipe and thereby presents curved outer surfaces.

Mounted upon the tracks 58 and 64 is the carriage of the spraying apparatus 12. The carriage as may be best seen in Fig. 2 includes a pair of castings 70 and 72 which have shapes substantially as illustrated in Fig. 1. A plurality of bolts such as bolts 74 and 76 hold the castings in assembled relationship to form the body for the carriage. The carriage includes a pair of outwardly directed arms 78 and 80 formed on the upper end thereof. Mounted within these arms 78 and 80 are wheels 82 and 84, these wheels being mounted on suitable axles 86 and 88. Immediately below the wheels 82 and 84 there are provided openings in the castings 70 and 72, these openings receiving the upper track 58; see Fig. 2. The wheels 82 and 84 ride upon the upper surface of track 58 whereby to support the carriage thereon.

The lower end of the carriage is also provided with outwardly extending arms, these arms being indicated by the numerals 88 and 92. Arms 90 and 92 also extend laterally outwardly as best seen in Fig. 2 whereby to accommodate a pair of wheels 94 and 96. The wheels 94 and 96 are supported upon axles that are mounted by means of bolts 98 and 100. The wheels 94 and 96 are spaced apart whereby to receive the lower track 64 therebetween, the track 64 extending through suitable apertures in the castings 70 and 72.

A second pair of wheels 89 is mounted on the carriage in position to contact the upper rail 58. A suitable housing 91 is provided to enclose each of the wheels 89.

It is to be noted that all of the wheels 82, 84, 89, 94 and 96 have concave grooves formed on the surface thereon to cooperate with the tracks 58 and 64. The wheels 82 and 84 contact the upper surface of track 58, wheels 89 contact the sides of track 58, and the wheels 94 and 96 contact the sides of track 64. The wheels 82 and 84 support the carriage in a vertical direction and the wheels 94 and 96 stabilize the carriage in a horizontal direction. This arrangement of the wheels provides for easy movement along the tracks 58 and 64 with a minimum of vibration and other irregularities in the path of travel of the carriage.

Means is provided to reciprocate the carriage upon the tracks 58 and 64. This reciprocating mechanism includes a motor 102, a speed reducer 104, and a pair of sprocket wheels 106 and 108 that drive a continuous or endless chain 110. Motor 102 is provided with an output shaft 112 on the end of which is mounted a V-shaped pulley 114. Connection is made between motor 102 and the speed reducer 104 by means of a V-shaped belt 116 that engages a pulley 118 attached to the input shaft 120 of the speed reducer 104. It will be seen that operation of motor 102 will serve to drive the speed reducer 104. The output shaft 122 of speed reducer 104 has mounted thereon the sprocket 108. Referring to Fig. 2 in the drawings there is shown a hollow channel shaped support 124 that supports a pedestal 126 on which is mounted speed reducer 104 and associated parts. The support member 124 also carries a pedestal 128 on which is mounted an axle 130 that supports sprocket wheel 106. Rotation of sprocket wheel 108 drives chain 110 which in turn drives the supporting sprocket wheel 106.

Referring now to Fig. 2 it will be seen that the chain 110 has fixedly attached thereto a stud 132. Stud 132 is provided with an enlarged head 134 that engages a pair of vertically position track members 136 fastened to the rear of casting 72. The track members 136 receive the head 134 of stud 132 and accordingly movement of stud 132 will move the carriage and its asso-

ciated parts. More particularly when the chain 110 is travelling in the direction of the arrow the carriage will be moving to the right as viewed in Figure 1, the stud 132 being positioned at the upper end of track 136. When the carriage reaches the vicinity of sprocket wheel 108, the stud 132 will be moved downwardly within track 136 and will reverse its direction of travel. This in turn will reverse the direction of travel of the carriage whereby to give a complete cycle of operation of the conveying mechanism.

The apparatus of the present invention is capable of coating articles travelling at extremely high rates. In order to coat articles travelling at high rates of speed it is necessary to oscillate the carriage and associated spray guns at correspondingly high rates of speed. Inasmuch as the carriage and its associated parts must reverse its direction of travel completely at each end of the spraying stroke, considerable stress is placed upon the operative parts due to the inertia of the carriage and its attachments. Means is provided to reduce the shock incident to the reversal of the direction of travel of the carriage at the end of its strokes and to aid in starting the carriage on its return stroke. Means is also provided to minimize vibration and related movements. To this end a heavy coiled spring 135 is provided adjacent each end of the path of travel of the carriage. One end of the spring is left open and free and the other end 137 of the spring is clamped between a nut 139 and an internally threaded cap 141. Both the nut 139 and the cap 141 are threaded upon a stud 143 that is firmly affixed as by welding to the end members 38-40. The external diameter of cap 141 is slightly less than the inner diameter of spring 135 whereby the cap supports the spring for a portion of its length. The position of the end of the spring 135 can be adjusted by means of the screw threads on the stud 143 and the cooperating threads on the nut 139 and cap 141. A pad 145 made of any suitable material, such as leather, is affixed to each side of the carriage in position to contact the free end of spring 135 when the carriage reaches the end of its path of travel. Preferably the springs 135 extend inwardly toward each other a distance such that the spring is compressed thereby absorbing any shock and vibration and also serving to aid in moving the carriage in the opposite direction.

Mounted on the translatable carriage is a pair of spray guns 138 that are supported on arms 140. Suitable clamps 147 and clamping nuts 149 are provided adjustably to position the spray guns 138 on arms 140. Arms 140 are carried by a rod 142 that is adjustably supported in a tubular member 144. More particularly rod 142 fits within tubular member 144 and is adjustable upwardly and downwardly by means of a clamp 146. Tube 144 is supported and carried by the housing members 70 and 72 of the carriage. Accordingly when the carriage moves along tracks 58 and 64 the spray guns are moved across the surface of the work piece 32.

Air for operation of the spray guns 138 is obtained through a line 148 that is connected through a suitable coupling 150 to a valve 152. From one side of valve 152 there extends an air line 154 which connects through another pair of lines 156 with spray guns 138.

Paint or other material to be sprayed is obtained through a material line or conduit 158 which is coupled as at 160 to a rigid pipe-like conduit 162 that is mounted on the carriage. The other end of conduit 162 connects with a line 164 which interconnects the source of material to be sprayed with the spray guns 138. Inasmuch as the carriage reciprocates upon the tracks 58 and 64, means is provided to hold the flexible lines 148 and 158 above the apparatus whereby to give free movement of the carriage. To this end a pair of telescoping support members 166 and 168 are provided, the lines 158 and 148 being mounted on the upper end of member 168. The lower support member 166 is mounted upon the support 124 which is stationary. A clamp 170 is provided so

that the level of the lines as supported by member 168 can be adjusted.

When the conduit 158 is connected to the spray guns 138, operation of the spray guns is obtained by introducing air from line 148 into the spray guns. This is accomplished by actuating the air control valve 152. Referring now to Fig. 6 the structure of valve 152 will be described in detail. Coupling pipe 150 is threaded as at 172 for attachment to a union member 174. Extending around the lower end of union member 174 is an outwardly directed flange 176. Surrounding the union member 174 is a ring 178 which has an inwardly directed flange 180 formed around the upper edge thereof. The inner diameter of flange 180 is smaller than the outer diameter of flange 176 whereby to cause engagement between these flanges. The lower internal circumference of ring 178 is provided with screw threads 182 which engage complementarily shaped screw threads on the body 184 of valve 152. Pipe 150 communicates with a chamber 186 formed in body 184 and further passages 188 and 190 are provided which communicate with pipe 192 which is threadedly mounted in body 184. Pipe 192 is connected through suitable coupling members to the air line 154.

A valve head 194 is reciprocably mounted within valve body 184. Also provided is a valve stem or control member 196 which is vertically and reciprocably mounted within valve body 184. The valve head 194 is attached to the control member 196 by means of a screw 198. The lower end of valve control member 196 is provided with a nut 200 having a rounded lower side 201 and a spring 202 is positioned between nut 200 and the valve member 184 whereby to urge valve head 194 to the seated position. In the seated position valve head 194 effectively closes passage 188 thereby preventing compressed air from reaching the spray guns 138.

In the operation of the spraying apparatus, it is desirable to have the spray guns in operation when they are positioned above and directed toward the work piece 32. At the ends of the path of travel of the carriage, it is highly desirable to turn off the spray guns to save material being sprayed and to eliminate difficulties occasioned by spraying paint and similar materials on parts of the spraying apparatus. Further it is desirable to have the spray guns travel past the edges of the work piece 32 as viewed in Fig. 1 to insure that the edges of the work piece are properly coated. Similarly it is necessary to turn on the spray guns at the proper moment when they again travel toward the work piece 32 on the return path of travel of the carriage.

It has been found that due to inertia and other factors the spray guns must be turned off at a point in time slightly prior to that at which the spray guns reach the edge of work piece 32. Similarly in turning on the spray guns it has been found necessary to initiate operation thereof at a point in time prior to the arrival of the spray guns along the edges of the work piece 32. Furthermore the point at which the spray guns are to be turned off and the point at which the spray guns are to be turned on do not coincide and accordingly separate means must be provided for turning off and turning on the spray guns 138.

To this end a cam and cam follower arrangement are provided in the present invention so that proper operation of the spray guns is obtained. In addition the cams and cam followers of the present invention are so constructed that they can be individually adjusted and universally adjusted to obtain the optimum efficiency of operation.

The means for operating the valve 152 include a double acting cam follower member generally designated by the numeral 204 and a plurality of cams 206, 208, 210 and 212. The cams 206 and 208 are mounted on a rod 218 that extends substantially parallel to and spaced between the tracks 58 and 64.

One end of rod 218 is received in an adjustable cam 75

mounting rod support 220 which is in turn supported by a C clamp 222 held together by a plurality of bolts 224. The support 220 is provided with an adjustment clamp 226 which permits adjustment of the position of rod 218 inwardly and outwardly with respect to the end member 38. A similar support structure is used to support the cams 210 and 212. Accordingly like reference numerals have been used in designating these parts. It would mean that this construction permits the cams to be adjusted vertically and horizontally and inwardly and outwardly with respect to the tracks 58 and 64.

Referring now to Fig. 3 the structure of the double acting cam follower 204 and the cams 210 and 212 will be described in detail. The double acting cam follower 204 includes a body 228 that is pivotally mounted on a stud 230 on casting 70. A bearing support plate 232 is mounted on the casting 70 in a recess therein and movement between the casting 70 and the bearing plate 232 is prevented positively by means of a pin 234. Three roller bearings 236 are disposed around and mounted upon the plate 232, the axis of rotation of each bearing lying parallel to the plane of rotation of the cam follower 204. The bearings 236 are positively retained in mounted position by means of a retainer ring 238 that surrounds the plate 232 and associated bearings.

A hardened contact plate 240 is mounted on the surface of body 228 that is disposed toward the bearings 238. Relative movement between the plate 240 and body 228 is prevented by the means of a plurality of pins 242.

As is best seen in Figure 3, body 228 is substantially teardrop shape and is positioned with the pointed end disposed upwardly. A relatively large recess 243 is formed in the larger portion of the body 228. Disposed within recess 243 is a ball bearing assembly 244 which provides for smooth rotation of the body 228 about the stud 230. In order to provide for easy repair a bearing sleeve 246 surrounds the stud 230 at the point at which the ball bearing assembly 244 is positioned. Inasmuch as the cam follower 204 is to assume any one of three distinct positions, the contact plate 240 is provided with suitably spaced recesses corresponding to each of the three positions. Rotation of the body 228 necessitates movement of the body 228 along the axis of stud 230 since the bearings 236 must be moved out of the grooves in plate 240 before they can be moved to the next groove. To this end there is provided a spring 248 and a cap 250 that are disposed between the head 252 of stud 230 and the bearing sleeve 246. The cap 250 serves to retain the spring 248 and the spring continually urges the body 228 toward the bearings 236. All of the parts are held in assembled relationship by means of a nut 251 which engages the threaded end of stud 230 and a washer 253. This structure insures that the cam follower retains the desired position when once in position, yet permits change in the position of the cam follower.

The upper or pointed end of body 228 has a slot formed therein to provide a pair of arms 254 and 256. These arms are provided with apertures which receive an axle 258 that supports a contact roller 260. In order to center roller 260 and insure its smooth operation a pair of washers 262 are provided on either side thereof. The roller 260 contacts an arm 264 which is pivoted on casting 70 by means of a screw 266. Arm 264 is actually disposed between the roller 260 and nut 200 as may be best seen in Figures 3 and 6.

In order to provide means for moving or changing the position of cam follower 204 a plurality of arms 265, 267 and 269 is provided. Arm 267 is diametrically opposed to roller 260 and the arms 265 and 269 extend radially outward along lines that intersect at the center of stud 230. Preferably the angular dispositions between arms 265 and 267 is the same as that between 267 and 269.

The structure of cams 210 and 212 is best shown in Figs. 4 and 5. Cam 210 will be described in detail. A circular collar 268 is provided, the internal diameter of the collar being slightly greater than the external diameter of rod 218. Extending radially outwardly from collar 268 is a projection 270 which is provided with an aperture. Mounted on either side of the projection 270 are plates 272 and 274, these plates having apertures that are aligned with the aperture in projection 270. Extending through the aligned apertures is a stud 276 having an enlarged portion 278, a head 280, and a threaded end 282. The stud, the plates and the projection are held in assembled relationship by means of a nut 284 that engages the threaded end of stud 276. The upper ends of plates 272 and 274 receive a rivet 286 on which is rotatably mounted a contact roller 288.

Referring now particularly to Figure 4 it will be seen that the plates 272 and 274 have a lower edge 290 that is straight for a portion thereof and is then curved upwardly as at 292. The plates are held in the position shown in Figure 4 by means of a coiled spring 293 having one end attached to the head 280 as at 294 and the other end attached to plate 272 as at 296.

Although the spring 293 holds the plates in the position shown in Figure 4, pressure applied from the right as viewed in Figure 4 can move the plates to the left, the plates pivoting about the stud 276. This is diagrammatically illustrated in Figure 3. In order to hold the cam in the desired position upon rod 218 and yet permit adjustment of the position of the cam, a set screw 298 is provided for fixing the position of the cam upon rod 218.

Referring now to Figure 3, the operation of the cam follower 204 and the cams will be explained in detail. When the cam follower is in the position shown in position A, valve 152 is open and causes operation of the spray guns 138. The cam follower remains in this position until moved to a different position by one of the cams. When the carriage and the associated cam follower move to the right from position A of Figure 3, the position of the cam follower is changed. More specifically, the finger 267 contacts the roller 286 of cam 210, thus moving cam follower 204 to position B. This movement of the cam follower removes roller 260 from contact with arm 264 and thus closes valve 152. The cam follower retains this position until moved.

When the cam follower approaches cam 212, the finger 269 will be in position to contact the roller 288. However, cam 212 will be ineffective to change the position of the cam follower since the cam will be moved to the position shown in dotted lines. After the cam follower passes cam 212 the direction of travel of the carriage is reversed and arm 269 again contacts roller 288. This time the cam will remain in an upright position due to the surface 290, and will be effective to move the cam follower to position C. This, in turn, initiates the operation of the spray guns 138 by opening valve 152. Continued movement of the carriage brings finger 267 into contact with the roller 288 of cam 210. Cam 210 will be ineffective to change the position of cam follower 204 and will be moved to the position shown in dotted lines. This sequence of operation is repeated when the cam follower engages the cams 206 and 208.

It will be seen that there has been provided a carriage and a cam and cam follower structure which fulfills all the objects and advantages set forth above. Although certain preferred forms of the invention have been given for the purpose of illustration, it is to be understood that various changes can be made therein without departing from the spirit and the scope of the invention. Accordingly, the invention is to be limited only as set forth in the following claims.

The invention is hereby claimed as follows:

1. The combination comprising a cam follower, said cam follower having an operative and an inoperative position, a pair of cams positioned adjacent said cam fol-

lower, means to move said cam follower and said cams relative to each other, one of said cams actuating said cam follower when the cam follower is moved past said cams in one direction, and the other of said cams actuating the said cam follower when the cam follower moves past said cams in the other direction.

2. The combination comprising a cam follower, said cam follower having operative and inoperative positions, a pair of cams positioned adjacent said cam follower, means to move said cam follower and said cams relative to each other, one of said cams being effective to move said cam follower to the inoperative position when said cam follower is moved past said cams in one direction, and the other of said cams being effective to move said cam follower to the operative position when said cam follower and said cams are moved past each other in the opposite direction.

3. The combination comprising a cam follower, said cam follower having an operative and an inoperative position, a pair of cams positioned adjacent said cam follower, means to move said cam follower and said cams relative to each other, one of said cams being effective only to move said cam follower to the operative position when said cam follower is moved past said cams, and the other of said cams being effective only to move said cam follower to the inoperative position when the cam follower is moved past said cams.

4. The combination comprising a cam follower, said cam follower having an inoperative and an operative position, a pair of cams mounted adjacent said cam follower, and means for moving said cam follower and said cams relative to each other, one of said cams being effective to actuate said cam follower when the cam follower moves in one direction past said cams, the other of said cams actuating said cam follower when the cam follower returns in the other direction.

5. The combination set forth in claim 4, wherein said cams include cam fingers pivotally mounted, spring means urging said cam fingers to an upright cam follower engaging position, and abutment means preventing pivotal movement of said cam fingers in one direction.

6. The combination set forth in claim 5, wherein said cam fingers are mounted to pivot only outwardly away from each other.

7. The combination comprising a cam follower, means rotatably mounting said cam follower for rotation about an axis, said cam follower being capable of rotation to an inoperative and an operative position, means to move said cam follower along a predetermined path of travel, means releasably to hold said cam follower in the assumed position until urged to another position, a pair of cams positioned adjacent the path of travel of said cam follower and in position to contact said cam follower, one of said cams being effective to rotate said cam follower to the inoperative position when the cam follower is moved past said cams in one direction, and the other of said cams being effective to rotate said cam follower to the operative position when said cam follower is moved past said cams in the opposite direction.

8. The combination comprising a cam follower, said cam follower having an operative and an inoperative position, means to reciprocate said cam follower along a predetermined path of travel, a pair of cams fixed adjacent each extremity of the path of travel of said cam follower, one of said cams at each end of said path of travel serving to move said cam follower to the inoperative position and the other of said cams serving to move said cam follower to the operative position.

9. The combination comprising a cam follower, said cam follower having an operative and an inoperative position, means to reciprocate said cam follower along a predetermined path of travel, a pair of cams fixed adjacent each extremity of the path of travel of said cam follower said cams being arranged in a line substantially parallel to the path of travel of said cam follower, the outer cam

of each pair of cams being effective to move said cam follower to the operative position and the innermost cam of each pair of cams being effective to move said cam follower to the inoperative position.

10. The combination comprising a cam follower, said cam follower having an operative and an inoperative position, means to reciprocate said cam follower along a predetermined path of travel, a support positioned adjacent each extremity of the path of travel of said cam follower, a pair of cams fixed to each support, said cams being arranged in a line substantially parallel to the path of travel of said cam follower, the outer cam of each pair of cams being effective to move said cam follower to the operative position, and the innermost cam of each pair of cams being effective to move said cam follower to the inoperative position, each of said cams being individually and independently adjustable with respect to each other and the associated support.

11. The combination comprising a cam follower, said cam follower having an operative and an inoperative position, means to reciprocate said cam follower along a predetermined path of travel, a pair of cams fixed adjacent each extremity of the path of travel of said cam follower, said cams being arranged in a line substantially parallel to the path of travel of said cam follower, each of said cams including a pivotally mounted cam finger, spring means urging said cam fingers to an upright cam follower engaging position, abutment means preventing pivotal movement of said fingers in one direction, the outer cam of each pair of cams being effective to move said cam follower to the operative position, and the innermost cam of each pair of cams being effective to move said cam follower to the inoperative position.

12. The combination as set forth in claim 11, wherein said cam fingers are mounted to pivot only outwardly 35 away from each other.

13. The combination, as defined in claim 8, wherein said cam follower is pivotally mounted and includes three cam engageable elements extending for selective engagement with certain of said cams, one of said elements between the others being actuated by said cams serving to move the cam follower to the inoperative position, a second element being actuated by the cam at one extremity of the path of travel serving to move the cam follower to the operative position, and a third element being actuated by the cam at the opposite extremity of the path of travel serving to move the cam follower to the operative position.

14. The combination, as defined in claim 12, wherein said cam follower is pivotally mounted and includes three cam engageable elements extending for selective engagement with certain of said cam fingers, one of said elements between the others being actuated by said innermost cam fingers to move the cam follower to the inoperative position, a second of said elements being actuated by one of said outermost cam fingers to move the cam follower to the inoperative position, and the third of said elements being actuated by the other of said outermost cam fingers to move the cam follower to the operative position.
